(57) **CLAIM**

The ornamental design for a nipple pad as shown and described.

DESCRIPTION

FIG. 1 is a perspective view of a nipple pad showing my new design;

FIG. 2 is a front elevation view thereof;

FIG. 3 is a side elevation view thereof;

FIG. 4 is a rear elevation view thereof;

FIG. 5 is a cross-sectional view taken through line 5-5 of FIG. 2; and,

FIG. 6 is an enlarged view taken along circle 6 of FIG. 5. The dot-dash broken lines in FIGS. 2 and 9 depict the boundaries of the enlargements that form no part of the claimed design.

1 Claim, 1 Drawing Sheet
